[57] **CLAIM**

The ornamental design for an elastic cincture band expansion device for the treatment of impotence, as shown and described.

DESCRIPTION

FIG. 1 is a front elevational view of a dome component of an elastic cincture band expansion device for the treatment of impotence embodying our new design, with all other sides being identical thereto;

FIG. 2 is a bottom plan view thereof;

FIG. 3 is a top plan view thereof;

FIG. 4 is a bottom left side perspective view thereof;

FIG. 5 is a top plan view of first embodiment of a cone component of the elastic cincture band expansion device for the treatment of impotence;

FIG. 6 is a front elevational view thereof;

FIG. 7 is a right side elevational view thereof;

FIG. 8 is a left side elevational view thereof;

FIG. 9 is a back elevational view thereof;

FIG. 10 is a bottom plan view thereof;

FIG. 11 is a bottom left side perspective view thereof;

FIG. 12 is an exploded left side perspective view of the dome and cone components in disassembled condition;

FIG. 13 is a left side perspective view thereof in assembled condition;

FIG. 14 is a left side bottom perspective view of an alternate embodiment of the cone component of FIG. 5;

FIG. 15 is a bottom plan view thereof;

FIG. 16 is a top plan view thereof;

FIG. 17 is a front elevational view thereof;

FIG. 18 is a right side elevational view thereof;

FIG. 19 is a left side elevational view thereof;

FIG. 20 is a rear elevational view thereof; and,

FIG. 21 is a bottom plan view thereof.
